[57] **CLAIM**

The ornamental design for a pharmaceutical tablet dispenser, as shown and described.

DESCRIPTION

FIG. 1 is a top plan view of a pharmaceutical tablet dispenser showing our new design;

FIG. 2 is a front elevational view thereof; the rear elevational view being a mirror image thereof;

FIG. 3 is a right side elevational view thereof; the left side elevational view being a mirror image thereof; and, FIG. 4 is top plan view of a second modified embodiment of FIG. 1.

The front, rear, left and right side elevational views of FIG. 4 embodiment are similar to as shown in FIGS. 2 and 3. The bottom is plain and unornamented.

FIG. 1**FIG. 3****FIG. 2***FIG. 4*
